US00D947280S

(12) **United States Design Patent** (10) **Patent No.:** **US D947,280 S**
(45) **Date of Patent:** **** Mar. 29, 2022**

(54) **LABEL SHEET ASSEMBLY WITH MATRIX CUTS**

(71) Applicant: **CCL Label, Inc.**, Framingham, MA (US)

(72) Inventors: **Evan Wang**, La Habra, CA (US); **Jay Sato**, Mission Viejo, CA (US)

(73) Assignee: **CCL LABEL, INC.**, Framingham, MA (US)

(**) Term: **15 Years**

(21) Appl. No.: **29/729,906**

(22) Filed: **Mar. 31, 2020**

(51) **LOC (13) Cl.** **19-08**

(52) **U.S. Cl.** **D19/10**

(58) **Field of Classification Search**

(57) **CLAIM**

The ornamental design for a label sheet assembly with matrix cuts, as shown and described.

DESCRIPTION

FIG. 1 is a perspective view of an embodiment of a label sheet assembly with matrix cuts showing our new design; FIG. 2 is a front view of FIG. 1 thereof; FIG. 3 is a back view of FIG. 1 thereof; FIG. 4 is a first side view of FIG. 1 thereof; FIG. 5 is a second side view of FIG. 1 thereof; FIG. 6 is a top view of FIG. 1 thereof; and, FIG. 7 is a bottom view of FIG. 1 thereof.

The broken lines in the figures are included for the purpose of illustrating portions of a carrier assembly and form no part of the claimed design.

1 Claim, 5 Drawing Sheets
